UNITED STATES PATENT OFFICE.

JACOB MACHER, OF NEW YORK, N. Y.

WATCH-CASE.

SPECIFICATION forming part of Letters Patent No. 307,968, dated November 11, 1884.

Application filed May 17, 1884. (No model.)

To all whom it may concern:

Be it known that I, JACOB MACHER, of the city, county, and State of New York, have invented certain new and useful Improvements 5 in Watch-Cases, of which the following is a full, clear, and exact description.

The object of my invention is to provide certain new and useful improvements in watch-cases, whereby the key or combined key and 10 push-pin can be withdrawn sufficiently from the pendant to clear the inner edge of the center, thus permitting the works to be passed into the case; but the push-pin or combined push-pin and key cannot be withdrawn entirely 15 from the pendant.

The invention consists in the combination, with a watch-case and its pendant, of a spring held in place in the pendant and a push-pin in the pendant, which push-pin is provided with 20 two offsets for limiting its movements in the pendant, between which offsets a tapered part is formed, all as will be fully set forth and described.

Reference is to be had to the accompanying 25 drawings, forming part of this specification, in which similar letters of reference indicate corresponding parts in all the figures.

Figure 1 is a longitudinal sectional elevation of the pendant and crown, the push-pin 30 and key being withdrawn. Fig. 2 is a longitudinal sectional elevation of the same, the push-pin and key being passed into the pendant. Fig. 3 is a sectional plan view of the 35 same on the line *xx*, Fig. 2. Fig. 4 is a longitudinal view of a modified construction of the combined key and push-pin.

The pendant A, of the usual construction, is provided with an internal shoulder, B, at or near the middle. The push-pin C is screwed 40 into a crown, D, fitting over the top of the pendant, and on the lower end of the push-pin the key E is formed, which engages with a suitable part of the works of the watch. A fixed collar, F, is formed on the push-pin at 45 the upper end of the key, and at the said collar F the thinner end of tapered part G is formed—that is, the part G increases in diameter from the collar F upward—and at the upper end of the part G an annular groove, 50 H, is formed, at the top of which a shoul-

der, J, is formed on the push-pin. In the pendant A a sleeve, K, fitting quite closely over the push-pin C, is held fixed within the pendant, either by means of a screw or in any other suitable manner. The lower end of the 55 fixed sleeve K is held a short distance from the shoulder B, and between the said shoulder and the lower edge of the sleeve K a V-shaped or other spring, L, is clamped on the push-pin. The spring L is held so that it cannot 60 be moved higher or lower in the pendant; but the push-pin can be moved through the spring and can be turned in the same.

In place of the groove H at the top of the part G the push-pin C can be provided with 65 a stem, H', the diameter of which is less than that of the push-pin proper or of the tapered part G. A rounded or beveled offset or shoulder, m, is formed at the top of the part G and directly below the groove H.

In place of the fixed collar F any other suitable projection can be provided on the top of the key or on the push-pin and key.

The operation is as follows: If works are to be placed into the case M, the push-pin must 70 be withdrawn, so as not to project inward from the center of the case. To this end the push-pin is pulled outward, and thereby the beveled or rounded shoulder m separates the free 75 ends of the spring L, and the tapered part G 80 slides through the spring L until the fixed collar F rests against the bottom edge of the spring L, as shown in Fig. 1. After the works have been inserted the push-pin is pushed back again, and thereby the tapered part G 85 separates the free ends of the spring L, and the ends of the spring snap into the groove H, thus holding the push-pin in place on the pendant. The push-pin is held in its normal position by the spring L, but can be pulled out of 90 the same if sufficient force is used; but it can never be withdrawn entirely from the pendant, as the fixed collar F prevents pulling the push-pin through the spring L. The push-pin can only be removed after removing the 95 sleeve K.

In double-face or hunting cases the pin C must have some play in the spring L, and to permit of this I have provided the stem H'. Thereby the push-pin can be moved up and 100

down in the pendant without acting on the spring L, but can act on the locking-spring of the front back.

Having thus described my invention, what I claim as new, and desire to secure by Letters Patent, is—

1. The combination, with a watch-case and its pendant, of a spring held in the pendant in such a manner that it cannot move in the direction of the length of the pendant, and of a push-pin provided with a collar or projection, and a short distance above the same with a shoulder and an annular groove of greater or less width, substantially as described.
- 15 2. The combination, with a watch-case and its pendant, of a spring held in the pendant, and of a push-pin passed through the spring and having two offsets, between which a ta-

pered part is formed, substantially as herein shown and described.

20

3. The combination, with a watch-case and its pendant, of the spring L, held in the pendant between the shoulder B and a sleeve, K, secured in the pendant, and the push-pin C, having a fixed collar, F, a part, G, and an annular groove, H, of greater or less width, substantially as herein shown and described.

25

4. A push-pin or key-pin for a watch-case, provided with a fixed collar or projection, F, and the groove H and shoulder m, substantially as herein shown and described.
